PROJECTING-MACHINE.

1,172,865.

Specification of Letters Patent.

Patented Feb. 22, 1916.

Application filed June 9, 1915. Serial No. 33,057.

To all whom it may concern:

Be it known that I, HUMBERT BIZZONI, a subject of the King of Italy, and a resident of the city of Chicago, county of Cook, and 5 State of Illinois, have invented certain new and useful Improvements in Projecting-Machines, of which the following is a specification.

My invention relates to projecting machines, and more specifically to that class thereof which are automatic in operation and designed for use primarily for advertising purposes.

The object of my invention is the production of a machine of the character mentioned which will be of durable and economical construction, one which will not be susceptible to readily becoming inoperative, and one which will be of high efficiency in use.

20 Other objects will appear hereinafter.

The invention consists in the combinations and arrangements of parts hereinafter described and claimed.

The invention will be best understood by 25 reference to the accompanying drawings forming a part of this specification, and in which,

Figure 1 is a substantially central vertical section of a projecting machine embodying the invention, Fig. 2 is a front elevation of the slide-carrying member included in the construction, or a view taken along the line 2—2 in Fig. 1, looking in the direction of the arrows, Fig. 3 is an enlarged detail section taken on line 3—3 of Fig. 2, Fig. 4 is a rear elevation of the construction with the rear wall of the housing broken away, and with the upper end portion of the construction shown in section, 35 Fig. 5 is a section taken on line 5—5 of Fig. 4, Figs. 6 and 7 are enlarged detail sections taken on lines 6—6 and 7—7 respectively of Fig. 1, Fig. 8 is an enlarged detail section taken on line 8—8 of Fig. 7, Fig. 9 is a section taken on line 9—9 of Fig. 1, Fig. 10 is a section taken on line 10—10 of Fig. 4, and Fig. 11 is a section taken on line 11—11 45 of Fig. 9.

The preferred form of construction, as 50 illustrated in the drawings, comprises a rigid metallic frame work or skeleton 15 at the front side of which are provided two spaced walls 16 and 17 forming an intermediate compartment A between the same.

55 The wall 16 is rigidly secured to the frame

15, the wall 17 being hinged at one edge 18 so as to permit of outward swinging of the opposite edge thereof in order to gain access to the compartment A. The wall 17 is locked in operative position by means of 60 latches 19 and 20 slidably mounted upon the inner side of said wall, said latches being adapted for engagement with slots provided for coöperation therewith in adjacent portions of frame 15, as clearly shown in 65 Fig. 10. A helical compression spring 21 coöperates with the member 19 for normally holding the same in operative position, the other latch being held in operative position by gravity. Externally positioned knobs 22 70 coöperate with latches 19 and 20 for manually moving the same to unlocking position.

One of the lateral walls 23 of the housing, as clearly shown in Fig. 5, is rigidly secured to the frame 15, the other lateral 75 wall 24 being hingedly connected with the rear wall 25 of the housing at 26, said rear wall being in turn hingedly connected at 27 with the rear edge of wall 23, the arrangement being such as to permit of the walls 80 24 and 25 being swung around and folded together, as shown in dotted lines in Fig. 5, so as to permit of ready access to the interior of the device. The wall 24 is locked in operative position by means of latches 28 85 which are slidably mounted upon the inner side of said wall adjacent the front edge thereof, as clearly shown in Fig. 10, said latches being adapted for engagement with sockets provided for coöperation therewith 90 in the frame 15. Said latches 28 are controlled by a key which may be inserted through an externally opening key hole 29, as will be readily understood. The free edge of the front wall 17 which is bent back 95 to form the end wall of compartment A is provided with a rearwardly projecting flange 30 which is adapted to overlap with the front edge of wall 24, thus making it necessary to first unlock the wall 17 before 100 the wall 24 may be swung outwardly. Co-operating with the rear wall 25 are also slidably mounted latches 31 and 32 arranged upon the inner side thereof, as clearly shown in Fig. 11, said latches being adapted for 105 engagement with sockets provided for coöperation therewith in frame 15 in the same manner as latches 19, 20 and 28. A helical compression spring 33 coöperates with the latch 31 for normally holding the same in 110

operative position, the latch 32 being held in this position by gravity. Interiorly positioned finger pieces 34 are provided upon the latches 31 and 32 for actuation 5 thereof.

Formed centrally in the wall 17 adjacent its upper edge is a circular opening 35 which opens into the rearward end of a projecting tube 36 which projects forwardly from said 10 wall, being provided at its front end with the usual lenses mounted in an adjustably mounted holder 36'. Formed in the wall 16 is a coaxial circular opening 37 behind which are mounted the conventional condensing lenses carried in a holder 38 mounted upon the inner side of wall 16, as clearly 15 shown in Fig. 1. Arranged directly behind the lens holder 38 is an arc lamp 39 with the upper end of which communicate electric 20 conductor wires 40. The lamp 39 is suspended from a substantially inverted U-shaped vertically adjustable support 41, said support being held in positions of vertical adjustment by means of thumb screws 42 25 which are threaded upon studs 43 projecting inwardly from depending arms 45. The ends or sides of member 41 are provided with elongated slots 46 to afford clearance for the studs 43, as clearly shown in Fig. 4. 30 The upper ends of arms 45 slidably engage with supporting bars 47 formed integral with frame 15, the arrangement being such as to permit of adjustment of the arc lamp toward and from the condensing lenses. Set 35 screws 48 coöperate with the members 45 for locking the same in positions of adjustment. With this arrangement then it will be seen that, through the vertical adjustment afforded the supporting element 41 and through 40 the horizontal adjustment afforded the supporting arms 45, the lamp may be adjusted vertically and horizontally in order to properly position the same relative to the lenses with which the same coöperates. 45 The upper wall of the housing of the device is cut away as at 49 to afford clearance for the upper end of the lamp and the support therefor, a supplemental housing 50 being arranged upon the upper end of the main 50 housing for inclosing said end of the lamp and the support therefor. The supplemental housing 50 is secured in position by means of nuts 51 which engage with studs 52 projecting upwardly from frame 15, as clearly 55 shown in Figs. 4 and 9.

Arranged in the compartment A is a circular slide-holder 53 which is mounted upon the front end of a shaft 54 rotatably mounted in suitable bearings secured to supporting bars 55 and 56 formed integral with the frame 15, at the front and rear sides thereof, as clearly shown in the several views. The slide-holder is formed adjacent its periphery with a plurality of equally spaced 60 rectangular openings 57, over which the 65

slides 58, which it is desired to project, are adapted to be arranged. The slides 58 are removably mounted in radially disposed channels formed in the front side of holder 53, plates 57 secured to the front side of 70 such holder overlapping and frictionally engaging with the longitudinal edges of said slides to hold the same in position over openings 57. Stops 60 formed upon the front side of holder 53, as clearly shown in 75 Fig. 3, are adapted to engage with the inner ends of slides 58 to limit inward movement thereof. The slide-holder 53 is so mounted that, in the rotation thereof, the slides 58 will be successively brought into registration with the projecting lenses in order to effect the projection of the pictures or matter upon said slides through the projecting tube 36.

Rotation of the shaft 54 is controlled by a 80 pair of ratchet wheels 61 and 62 secured to the front and rear ends respectively of said shaft. Coöperating with the ratchet 61, as clearly shown in Figs. 6 and 7, is a pawl 63 which is pivoted at 64 to the supporting bar 90 85 55. A helical tension spring 65 coöperates with the pawl 63 to normally hold the same in operative relation with the ratchet wheel 61 in order to prevent positive or forward rotation of the shaft 54, it being necessary, 95 therefore, with this arrangement in releasing the shaft 54 so as to permit of positive rotation thereof, to first rock the pawl 63 to inoperative position. For this purpose the pawl 63 is formed with a substantially 100 horizontally disposed extension 66 which is adapted for engagement by mechanism hereinafter described in effecting releasing movement of pawl 63. Coöperating with the ratchet wheel 62, as clearly shown in 105 Figs. 4 and 7, is a pawl 67 hinged at 68 to a supporting arm 69 projecting upwardly from supporting bar 56. A helical tension spring 70 coöperates with the pawl 67 to normally hold the same in operative relation 110 with said ratchet wheel 62 in order to prevent retrograde rotation of the shaft 54.

Arranged below the shaft 54 is a shaft 71 rotatably mounted in suitable bearings secured to frame bars 72 and 73 formed integral with frame 15. Fixed to the shaft 71 is a gear 74 with which meshes a pinion 75 fixed to a shaft 76 which is mounted in suitable bearings also secured to supporting bars 72 and 73. The shaft 76 also carries a worm 115 120 wheel 77 which meshes with a worm 78, as clearly shown in Fig. 4, provided upon the power shaft 79 of an electric motor 80, said motor and power shaft being suitably mounted upon bearings arising from the bottom of the housing of the machine. Conductor wires 81 are shown for coöperation with the motor 80, said wires together with the conductor wires 40 which coöperate with the lamp 39, being united for connection 125 130

with a source of electrical energy. With this arrangement it will be seen that upon operation of the motor the gear 74 will be rotated.

5 Formed in one side of the gear 74, as clearly shown in Fig. 8, is an annular channel 82 in the bottom of which is formed an annular slot 83, the inner and outer parts of the gear which are thus completely severed 10 from each other being connected by straps 84. Mounted for sliding adjustment in the slot 83 is a plurality of tappet members 85 which are adjustably fastened to the gear 74 by means of screws 86 and co-operating nuts 15 87. The inner ends of the tappets 85 are square in order to prevent relative rotation of the same in the slot 83. The outer end 85 of each tappet is angularly formed for engagement with the extension 66 of the pawl 20 63, as clearly shown in Fig. 7, so that, in the rotation of gear 74, the pawl 63 will be successively moved to inoperative position by reason of the successive engagement of the 25 ends 88 of the tappets with said extension 66.

Mounted upon the shaft 54, adjacent the ratchet 61, is a gear or sprocket wheel 89 which is positioned coplanar with the inner or base portions of the tappets 85, as clearly 30 shown in Fig. 8. The arrangement is such that, in the rotation of the gear 74, the base portions of the tappets 85 will successively engage with the teeth of member 89 in order to effect intermittent rotation thereof and 35 hence of the slide-holder 53 carried by the shaft 54. The extension 66 of the pawl 63 is so positioned relative to the member 89, that said pawl will be moved to releasing position by each tappet extension 88 before 40 the tappet proper engages with said member 89. Also, the parts are so proportioned that the movement imparted to the slide-holder by each tappet in the engagement thereof with the member 89, will be just sufficient to 45 carry one slide from projecting position and to carry the succeeding slide in projecting position. Thus, the successive engagement of the tappets with the member 89 will serve to intermittently move the slide-holder to 50 successively position the slides carried thereby for projection from the machine. Upon the passage of a tappet from engagement with the member 89 and the extension 66 of the pawl 63, the latter will immediately 55 move to operative position under the influence of spring 65 so as to prevent excess movement of the slide-holder through inertia. By spacing the tappets along the slot 83, it is, of course, apparent that the 60 duration of exposure of the slides projected from the machine may be governed as desired and any number of tappets may be employed, depending upon the length of time it is desired to expose each slide.

65 Through the hinged mounting of the

front wall 17, access may be readily gained to the compartment A for the changing of the slides in the slide-holder without disturbing any other part of the mechanism. Access to the interior of the machine for adjustment of the tappets, or for any other purpose, may be readily and easily gained by unlocking of the walls 24 and 25 and swinging of the same to the dotted line position shown in Fig. 5.

70 With the construction set forth then, it will be seen, that a machine is provided which, in operation, is entirely automatic, the slides carried by the slide-holder upon which advertising or other matter may be 80 arranged, being successively projected from the machine onto the screen which is used in connection with the machine.

75 While I have illustrated and described the preferred form of construction for carrying 85 my invention into effect, this is capable of variation and modification without departing from the spirit of the invention. I, therefore, do not wish to be limited to the precise details of construction set forth, but 90 desire to avail myself of such variations and modifications as come within the scope of the appended claims.

Having described my invention what I 95 claim as new and desire to secure by Letters Patent is:

1. In a projecting machine, the combination of a projecting tube; a rotatable slide-holder adapted to accommodate a plurality of slides and successively carry the same into registration with said projecting tube upon rotation of said holder; a driving element; and means for imparting intermittent rotation to said holder upon operation of said driving element, said means being adjustable whereby the periods of movement and rest of said slide-holder may be varied, substantially as described.

100 2. In a projecting machine, the combination of a projecting tube; a rotatable slide-holder adapted to accommodate a plurality of slides and successively carry the same into registration with said projecting tube upon rotation of said holder; a driving element; means for imparting intermittent rotation to said holder upon operation of said driving element, said means comprising a rotary element adapted, upon rotation, to rotate said slide-holder; and tappets adapted for 105 engagement with said rotary element for moving the same, substantially as described.

110 3. In a projecting machine, the combination of a projecting tube; a rotatable slide-holder adapted to accommodate a plurality of slides and successively carry the same 115 into registration with said projecting tube upon rotation of said holder; a driving element; means for imparting intermittent rotation to said holder upon operation of said driving element, said means comprising a 120

125

5 pets adapted for adjustment toward and from each other and adapted to simultaneously successively engage with and move said pawl to releasing position and to successively engage with and move said projections, substantially as described.

10 11. In a projecting machine, the combination of a projecting tube; a movably mounted slide-holder adapted to accommodate a plurality of slides and carry the same into successive registration with said projecting tube upon movement of said holder; a driving element; means for imparting intermittent movement to said holder upon operation of said driving element, said means comprising a member having projections adapted, when moved, to actuate said slide-holder; a pawl for normally locking said slide-holder against forward movement; a 15 rotary member connected for continuous rotation by said driving element and having an annular slot therein; and a plurality of tappets adjustably mounted in said slot and adapted, upon rotation of said member, to 20 successively engage with and move said pawl to releasing position and to successively engage with and move said projections, substantially as described.

25 12. In a projecting machine, the combination of a projecting tube; a movably mounted slide-holder adapted to accommodate a plurality of slides and carry the same into successive registration with said projecting tube upon movement of said holder; a driving element; means for imparting intermittent movement to said holder upon operation of said driving element, said means comprising a member having projections adapted, when moved, to actuate said slide-holder; a pawl for normally locking said slide-holder against forward movement; means operable by said driving element and adapted to successively engage with and move said pawl to releasing position and to 30 35 40 45 successively engage with and move said projections; and means for preventing retro-

grade rotation of said slide-holder, substantially as described.

13. In a projecting machine, the combination of a housing; a projecting tube mounted on said housing; a movably mounted slide-holder adapted to accommodate a plurality of slides and carry the same into successive registration with said projecting tube, upon movement of said holder; a 50 source of illumination arranged in said housing for coöperation with said projecting tube; supporting means for said source of illumination permitting of adjustment of said source of illumination in a vertical 55 plane passing through the axis of said projecting tube, said supporting means comprising a substantially inverted U-shape member upon the central portion of which said source of illumination is mounted; 60 members mounted for horizontal adjustment in the upper end of said housing; and a connection between said last mentioned members and the sides of said inverted U-shape member permitting of vertical adjustment 65 of the latter, substantially as described. 70

14. In a projecting machine, the combination of a housing having a supplemental compartment at its front side independent of the interior of said housing; a projecting tube mounted on the front wall of said supplemental compartment; a movably mounted slide-holder arranged in said supplemental compartment adapted to accommodate a plurality of slides and carry the 75 same into successive registration with said projecting tube, upon movement of said holder; and means mounted in said housing for intermittently actuating said slide-holder, substantially as described. 80 85

In testimony whereof I have signed my name to this specification in the presence of two subscribing witnesses.

HUMBERT BIZZONI.
